DESIGN FOR A SHELL OF A PITOT STATIC TUBE

Paul Kollsman, New York, N. Y.

Application August 25, 1938, Serial No. 79,565

Term of patent 14 years

To all whom it may concern:

Be it known that I, Paul Kollsman, a citizen of the United States and a resident of the city of New York, county of New York, and State of New York, have invented a new, original, and ornamental Design for a Shell of a Pitot Static Tube, of which the following is a specification, reference being had to the accompanying drawing, forming part thereof.

Fig. 1 is a side elevational view of a shell of a Pitot static tube showing my new design.

Fig. 2 is a front elevational view thereof.

I claim:

The ornamental design for a shell of a Pitot static tube, substantially as shown.

PAUL KOLLSMAN.
